LASTING MACHINE

Fred Ricks and John William Pratt, Leicester, England, assignors to United Shoe Machinery Corporation, Borough of Flemington, N. J., a corporation of New Jersey

Application June 27, 1939, Serial No. 281,406
In Great Britain September 2, 1938

21 Claims. (Cl. 12—14)

This invention relates to lasting machines, and more particularly to machines for lasting the toe ends of shoes. The invention is herein illustrated as applied to a power-operated toe-lasting machine of the same general character as disclosed in United States Letters Patent No. 2,134,148, granted on October 25, 1938, upon an application of W. T. B. Roberts, but modified in certain respects as further disclosed in United States Letters Patent No. 2,138,308, granted on November 29, 1938, also upon an application of W. T. B. Roberts. It is to be understood, however, that in various novel aspects the invention is not thus limited in its applicability.

The machine to which the invention is herein shown as applied is a power-operated machine provided with toe-embracing wipers which wipe the upper around the toe end of the last heightwise of the last and thereafter wipe its marginal portion inwardly over an insole on the last, the machine having also upper-clamping fingers which cooperate with the wipers to apply a pull to the upper heightwise of the last and thereafter control the margin of the upper as it is wiped inwardly over the insole. An object of the present invention is to improve the operation of such a machine on comparatively light-weight uppers, and more particularly to afford better insurance against the presence of objectionable wrinkles which would be visible in the upper of the finished shoe at the sides of the toe due to the tendency of the wipers to deflect the marginal portion of the upper at the sides of the toe in a heelward direction in wiping it inwardly over the insole. For the purpose in view, the invention provides means for more effectively wiping the upper heightwise of the last at the sides of the toe, so that by reason of the tightness with which the upper is conformed to the last in those locations the action of the wipers in wiping its marginal portion inwardly over the insole will not, under any conditions, cause wrinkles which are visible in the finished shoe. As herein illustrated, the machine is provided with auxiliary wipers arranged to cooperate with the usual toe wipers, which may be termed the main wipers, in wiping the upper heightwise of the last, the auxiliary wipers comprising plates pressed yieldingly inward against the upper independently of the main wipers at the sides only of the toe to supplement the wiping action of the main wipers. In the construction shown, these plates rest on the main wipers and are movable upwardly with them, the shoe being positioned bottom upward. As further illustrated, the auxiliary wipers are

so mounted as to permit them to adjust themselves to the shoe about axes extending heightwise of the shoe; and they are also so formed that they increase progressively in thickness heightwise of the shoe toward its heel end to present wiping edges inclined heightwise of the shoe toward the end of the toe in a direction away from the edge of the insole. This gives them a tendency to deflect the upper toward the end of the toe to compensate for the tendency of the main wipers later to deflect it in the opposite direction in wiping its margin inwardly over the insole. The auxiliary wipers are controlled by mechanism which moves them relatively to the main wipers in directions substantially perpendicular to the wiping edges of the latter into upper-engaging positions and later retracts them to make way for upper-fastening means with which the machine is provided. The construction shown is further such that, under the influence of springs which control them, the auxiliary wipers are forced to some extent inwardly over the insole as soon as they are in such a relation to the shoe as to permit that action, so that they begin the wiping of the marginal portion of the upper over the insole in directions substantially perpendicular to the edge of the insole before the main wipers receive their overwiping movements both widthwise and lengthwise of the shoe. This tends to prevent any undue deflection of the margin of the upper at the sides of the toe lengthwise of the shoe thereafter by the main wipers. As they are thus forced inwardly over the insole, the auxiliary wipers have a further tightening effect on the upper, since in the construction shown the previously mentioned upper-clamping fingers actually clamp portions of the margin of the upper on the auxiliary wipers instead of on the main wipers. During a portion of the overwiping movements of the main wipers the upper remains thus clamped, and since the auxiliary wipers are stationary at this time, there is a further tendency to prevent undue deflection of the upper lengthwise of the shoe by the main wipers.

The above and other features of the invention, including various novel details of construction and combinations of parts, will now be more particularly described with reference to the accompanying drawings and thereafter pointed out in the claims.

In the drawings, Fig. 1 is a plan view of a portion of a machine to which the invention is applied, showing the auxiliary wipers and the mechanism for control-

ling them, the main wipers and the upper-clamping fingers being shown in broken lines;

Fig. 2 shows a portion of the structure in elevation, as viewed in the direction of the arrow II on Fig. 1;

Fig. 3 is a section on the line III—III of Fig. 1;

Fig. 4 shows one of the auxiliary wipers and a carrier on which it is mounted, as viewed in the direction of the arrow IV on Fig. 1;

Fig. 5 is a section on the line V—V of Fig. 1; and

Fig. 6 is mainly a plan view of parts shown in Fig. 1, with the parts in the positions which they occupy immediately after the wiping of the upper per heightwise of the last.

In view of the disclosures in the previously mentioned Letters Patent, only as much of the machine as it is necessary to refer to for an understanding of the invention is shown in the drawings or will be described in detail. The machine is provided with a pair of upper-clamping fingers 1 and a pair of toe-embracing wipers 3 with which the fingers have heretofore cooperated directly to clamp the upper during a portion of the toe-lasting operation. The shoe is supported bottom upward, and the wipers initially are in a plane spaced a substantial distance below the toe end of the insole. In the operation of the machine the fingers 1, which are positioned initially as indicated by broken lines in Fig. 1, are moved lengthwise of the shoe toward the end of the toe and are also swung apart to insure the spreading of the margin of the upper materials from over the insole, and as soon as they pass the edge of the insole they are moved downwardly toward the wipers with the upper materials outspread between them and the wipers. The wipers are thereafter moved upwardly, while embracing the upper closely about the toe and pressing it inwardly against the last, to wipe the upper heightwise of the last, and early in their upward movement the upper becomes clamped by the fingers 1 which are thereafter lifted with the wipers. Accordingly, an upward pull is applied to the upper while it is being wiped toward the edge of the insole. After the completion of the upward movement of the wipers the shoe is forced downwardly a short distance to bring the insole into proper relation to the wipers for the latter to wipe the marginal portion of the upper inwardly over it, and the wipers are then advanced and closed to perform this overwiping operation. The fingers 1 first advance lengthwise of the shoe with the wipers while maintaining control of the margin of the upper and are then moved reversely outward and are swung farther apart, as indicated by broken lines in Fig. 6, to make way for tack-inserting devices which are moved inwardly over the wipers and downwardly into positions to fasten the upper to the insole. The sequence of operations is thus substantially as disclosed in Letters Patent No. 2,138,308.

For purposes of this invention there are provided auxiliary wipers 5 comprising plates which rest on the top of the main wipers 3 and are movable upwardly and downwardly with them. These auxiliary wipers in the construction herein shown are arranged to engage the upper along the sides of the toe from the corners of the toe heelwardly, but terminate somewhat short of the heelward ends of the main wipers; and in order that they may be used on shoes of various shapes or sizes, their wiping edges are curved but little lengthwise of the shoe. Each wiper 5 is mounted on a carrier 7 in such manner as to permit it to

adjust itself to the shoe about an axis extending heightwise of the shoe, the location of this axis being indicated at 9 (Fig. 1). The carrier 7 has a bifurcated portion 11 (Fig. 2), and the wiper 5 is recessed on its lower side, as indicated at 13 (Fig. 1) to receive the lower fork of the bifurcated portion of the carrier. This lower fork has an end 15 curved about the axis 9 and engaging a curved wall of the wiper 5 formed in the recess 13. The wiper is retained on the carrier by a pin 17 fixed in the carrier and extending through a slot 19 in the wiper, the center of curvature of this slot coinciding with the axis 9.

Each wiper carrier 7 is rigidly connected to a bar 21 by a pin 23 extending through the bar and through a cylindrical portion 25 of the carrier which is mounted in a socket in the bar. Each bar 21 extends laterally of the machine in substantially perpendicular relation to the edge of the insole of that portion of a shoe on which the auxiliary wiper 5 on the bar operates. The bar has extending downwardly from it, between its opposite ends, a ball-ended stud 27 (Fig. 3) the ball end of which fits between two plates 28 recessed to receive it, these plates being mounted to slide along a guideway 29 in a bracket 31. Each bracket 31 is secured below the bar 21 to a bracket 33 which is mounted on one of a pair of wiper-supporting castings 32 through which upward and downward movements are imparted to the wipers, these castings corresponding to the castings 85 of Letters Patent No. 2,134,148. The guideway 29 associated with each bar 21 serves to guide the bar for lengthwise inward movement in a direction substantially perpendicular to the edge of the insole at the side of the toe. A retaining member 34 fastened to each bar 21 has a portion formed to extend under a flange 36 on the bracket 31 to prevent any accidental lifting of the bar far enough to withdraw the plates 28 from the guideway 29. In order to permit either auxiliary wiper 5 to be adjusted lengthwise of the shoe along the underlying wiper 3, each bracket 31 is pivotally connected by a pin 35 to the bracket 33, and a clamping screw 37 is provided for holding the bracket 31 in adjusted position, this screw being threaded in the bracket 33 and extending through a slot 39 in the bracket 31.

For imparting inward and outward movements at the proper times in the cycle of operations of the machine to the two bars 21 to move the auxiliary wipers 5 into engagement with the upper and to withdraw them to inoperative positions, there is mounted on the cam shaft shown at 253 in Letters Patent No. 2,134,148 a cam the position of which is illustrated diagrammatically by broken lines at 41 (Fig. 1), and a cam lever 43 is pivotally mounted on a vertical stud 45 below the shaft and has a rearwardly extending arm 47 carrying a roll 49 rotatably mounted on an upwardly extending stud 51, the roll being engaged by the cam. The lever 43 has a forwardly extending arm 53 normally connected by means hereinafter described to the left-hand end of a link 55. This link is pivotally connected at its right-hand end by a pin 57 to a forwardly extending arm 59 of a horizontal lever 61 substantially midway of the length of the arm, the lever 61 being mounted on a stud 63 supported by the machine frame a portion of which is shown at 65. The lever 61 has also a rearwardly extending arm 67. The front end of the arm 59 of the lever is connected by means hereinafter described to the outer end of the left-hand bar 21, and the rear end of the arm 67, which is bifur-

cated; is pivotally connected to the left-hand end of a rod 69 by a pin 71, this rod extending across the machine behind the wipers to a position near the right-hand side of the machine. At its right-hand end the rod 69 is pivotally connected to one arm 73 of a horizontal bell-crank lever 75 by a pin 77. The bell-crank lever 75 is pivotally mounted on a vertical stud 79 on the frame and has an arm 81 connected to the outer end of the right-hand bar 21 by means similar to that which connects the arm 59 to the left-hand bar. The construction is accordingly such that when the cam lever 43 is swung in a counterclockwise direction (Fig. 1) by the cam 41, the lever 61 is swung in the same direction and imparts inward movements toward the shoe to both the auxiliary wipers 5 in directions substantially perpendicular to the portions of the edges of the main wipers 3 which are under the auxiliary wipers when the latter are in engagement with the shoe. When the cam lever 43 is swung in the opposite direction the auxiliary wipers are retracted to inoperative positions.

The front end of each of the arms 59 and 81 carries a depending trunnion block 83 rotatable on a vertical stud 85 on the arm, and a second block 87 lying between the forks of a downwardly extending bifurcated portion 89 of the block 83 is pivoted to the latter by means of forwardly and rearwardly extending studs 91 projecting from the block 87 into coaxial holes in the forks. The block 87 has a substantially horizontal bore 93 perpendicular to the axis of the studs 91, and through this bore extends the cylindrical outer end portion of the bar 21. A sleeve 95 is threaded on this portion of the bar and also extends through the bore 93. The inner end of the sleeve 95 has a flange 97 against which bears one end of a spring 99, and the other end of this spring 40 bears against a knurled head 117 formed on a second sleeve 115 which surrounds the sleeve 95 and is threaded in the bore 93 of the block 87. It will thus be seen that the auxiliary wiper 5 is forced yieldingly against the shoe through the spring 99. Expansion of the spring is limited by engagement of a flange 101 on the sleeve 95 with the outer face 103 of the block 87. Formed on the outer end of the sleeve 95 is a knurled head 102 by which the sleeve may be turned to adjust the bar 21 and its wiper 5 toward or from the shoe. A member 104 is clamped on the outer end of the bar 21 by a screw 106 and has an inwardly extending portion 107 slidably movable in a guideway 109 in the block 87 to prevent rotation 55 of the bar. To afford an indication as to the adjusted position of the bar 21, a pin 111 is mounted in a depending lug 113 on the portion 107 of the member 104 and has on its end an index mark arranged to cooperate with a scale on the block 87. It will be evident that by turning the sleeve 115 by means of its knurled head 117 the amount of compression of the spring 99 may be varied to vary the force with which the auxiliary wiper 5 is pressed against the shoe.

As illustrated in Fig. 2, the trunnion blocks 83 are at such a height that initially the bars 21 and the auxiliary wipers 5 are inclined somewhat downwardly toward the main wipers 3. If desired, springs 119 connected to pins on the blocks 87 and to other pins on the lever arms 59 and 81 may be provided to assist gravity in holding the wipers 5 down on the wipers 3. When the wipers 3 are at the limit of their upwiping movement the auxiliary wipers 5 rest substantially flat upon them. It will be understood that the required

upward and downward swinging movements of the bars 21 as the wipers 3 are raised and lowered are permitted by the pivotal connections 91 between the blocks 87 and 83.

The means previously referred to for connecting the forwardly extending arm 53 of the cam lever 43 to the link 55 is so constructed that the arm may be disconnected from the link and the link held stationary to render the auxiliary wipers 5 inoperative if the machine is to operate upon work of such a character that use of the auxiliary wipers is unnecessary or even undesirable. The link 55 is pivotally connected at its outer end by a pin 123 to a lug 121 formed on a forwardly extending lever 125 which is pivotally mounted on the same stud 45 as the lever 43. The arm 53 of the lever 43 has formed thereon a curved segment 127 the center of curvature of which is at the axis of the stud 45. This segment has a horizontal plane lower face 129 (Fig. 5) spaced 20 a substantial distance above a parallel plane upper face 131 of a plate 133 rigidly connected to the machine frame. The faces 129 and 131 serve as guideways for upwardly and downwardly extending portions 135 and 137 of the lever 125. Formed in these portions of the lever is a bore 139 in which a pin 141 is movable vertically. When the lever 125 is in one position the pin 141 may enter a hole 143 in the segment 127, and when the lever is in another position the pin may enter a hole 145 in the stationary plate 133. Proper alignment of the pin with these holes is determined by stops 147 and 149 mounted respectively in the segment 127 and in the plate 133, these stops being arranged to abut respectively against the portions 135 and 137 of the lever 125. In order that the pin 141 may be readily moved into the hole 143 or the hole 145, it has mounted therein a rearwardly extending pin 151 which lies in a radial slot 153 in a circular plate 155. This plate is mounted on the rear end of a shaft 157 rotatable in the lever 125, the shaft having a handle 159 on its front end for turning it. It will be understood that when the pin 141 is in the hole 143 the auxiliary wipers 5 are operated by the cam lever 43. If the operator wishes to render these wipers inoperative, he turns the shaft 157 in the proper direction to withdraw the pin 141 from the hole 143, swings the lever 125 to the left until its downwardly extending portion 137 engages the stop 149, and then by further turning the shaft 157 moves the pin 141 into the hole 145 in the fixed plate 133. Thereafter the arm 53 of the lever 43 swings idly when the machine is operated. A spring 161 stretched between a pin 163 on the circular plate 155 and a pin on the lever 125 tends to maintain the pin 141 in either the hole 143 or the hole 145, since the pin 163 is so located on the plate 155 that it is carried past a dead center position as the pin 141 is moved into either hole. When the pin 141 is in the hole 145 the auxiliary wipers 5 are completely withdrawn from over the main wipers 3. This facilitates removal of the main wipers whenever such removal is necessary.

The auxiliary wipers 5 are so formed that they increase progressively in thickness heightwise of the shoe from the ends thereof which are adjacent to the corners of the toe to their other ends, as illustrated in Fig. 4, their upper wiping edges being upwardly inclined toward the heel end of the shoe. By reason of this construction they have a tendency, as they are moved upwardly in wiping contact with the upper at the sides of the toe, to crowd or deflect the portions 75

of the upper on which they act toward the end of the toe and thus to compensate for the tendency of the main wipers later to deflect the upper at the sides of the toe in a heelward direction as they wipe its margin inwardly over the insole. This action is supplemental to the tightening effect of the auxiliary wipers on the upper in wiping it heightwise of the last, and affords increased insurance against any such deflection of the upper lengthwise of the last by the main wipers as to produce wrinkles visible in the finished shoe.

In the operation of the machine the auxiliary wipers 5 are moved inwardly from the positions in which they are shown in Fig. 1 into engagement with the upper at the sides of the toe by the time the main wipers 3 begin their upwiping movement. As the auxiliary wipers are forced against the upper, the springs 99 are compressed more or less, so that the edges of these wipers bear firmly on the upper, and their edges may, in fact, project inward slightly beyond the edges of the main wipers 3 which are also in engagement with the upper. Prior to the upwiping operation the upper-clamping fingers 1 are moved outwardly from over the insole and downwardly toward the wipers. As the main wipers 3 are moved upwardly, the auxiliary wipers 5 move with them, so that the portions of the upper engaged by these auxiliary wipers are subjected to a double wiping action. It will be evident that by reason of the manner in which the auxiliary wipers are mounted and controlled, they are enabled to follow more closely than the main wipers any variations in the contour of the shoe. Early in the upwardly movement of the wipers the marginal portion of the upper is clamped between the auxiliary wipers and the fingers 1, after which the fingers rise with the wipers and cooperate with them to apply a pull to the upper. After the wipers have completed their upward movement the shoe is depressed a short distance to position the toe end of the insole in the proper plane for the main wipers 3 to wipe the upper inwardly over it. As soon as the relation between the shoe and the auxiliary wipers permits, these wipers are forced a short distance inwardly over the insole by expansion of the springs 99, as illustrated in Fig. 6, so that they begin the wiping of the upper over the insole in directions substantially perpendicular to the edge of the insole. Thereafter the main wipers are advanced and closed to wipe the marginal portion of the upper fully inward over the insole. During a portion of these movements of the main wipers the upper is still clamped between the fingers 1 and the auxiliary wipers, and since the auxiliary wipers do not partake of the movements of the main wipers, but are held stationary, the result is that the upper is maintained under greater tension, with less tendency for it to be deflected in a heelward direction at the sides of the toe, than if it were clamped by the fingers 1 on the main wipers 3 as heretofore. The auxiliary wipers are thus held stationary until the clamping fingers 1 have been moved outwardly over the margin of the upper and are nearly ready to descend to their inoperative positions indicated by broken lines in Fig. 6, whereupon the auxiliary wipers are retracted from over the main wipers to the positions indicated by broken lines also in Fig. 6. This provides ample clearance for the tack-inserting devices with which the machine is provided to move inwardly over the main wipers after the latter have performed a second overwiping operation as

heretofore. As these devices are retracted after the driving of the upper-fastening tacks, the auxiliary wipers are moved inwardly over the main wipers to the positions in which they are shown in Fig. 1 before the machine comes to a stop at the end of the cycle.

Having described the invention, what we claim as new and desire to secure by Letters Patent of the United States is:

1. In a lasting machine, wipers for pressing an upper inwardly against a last and wiping it heightwise of the last around the end and along the sides of the toe, and additional wipers arranged to act on the same portions of the upper as said first-named wipers at the sides only of the toe to press the upper inwardly against the last and wipe it heightwise of the last at the time when said first-named wipers are thus acting on the upper, said additional wipers being arranged to engage the upper in locations nearer the edge of the last bottom than the first-named wipers.

2. In a lasting machine, wipers for pressing an upper inwardly against a last and wiping it heightwise of the last around the end and along the sides of the toe, additional wipers arranged to act on the same portions of the upper as said first-named wipers at the sides only of the toe to press the upper inwardly against the last and wipe it heightwise of the last at the time when said first-named wipers are thus acting on the upper, and mechanism for moving said additional wipers inwardly into upper-engaging positions relatively to the first-named wipers after a shoe has been positioned between them, said mechanism including springs arranged to be subjected to stress to hold the additional wipers pressed yieldingly inward against the upper.

3. In a lasting machine, wipers for pressing an upper inwardly against a last and wiping it heightwise of the last around the end and along the sides of the toe, said wipers being mounted for swinging movements to close them inwardly at the sides of the toe, additional wipers arranged to act on the same portions of the upper as said first-named wipers at the sides of the toe to press the upper inwardly against the last and wipe it heightwise of the last and thus to increase the effectiveness of the wipe in those locations, and means for imparting to said additional wipers rectilinear movements widthwise of the last relatively to said first-named wipers into positions to act on the upper after a shoe has been positioned between them.

4. In a lasting machine, wipers for pressing an upper inwardly against a last and wiping it heightwise of the last around the end and along the sides of the toe, additional wipers arranged to act on the same portions of the upper as said first-named wipers at the sides only of the toe to press the upper inwardly against the last and wipe it heightwise of the last, and bars connected to said additional wipers and movable lengthwise relatively to the first-named wipers in directions widthwise of the last to carry said additional wipers into engagement with a shoe positioned between them.

5. In a lasting machine, wipers for pressing an upper inwardly against a last and wiping it heightwise of the last around the end and along the sides of the toe, and additional wipers arranged to act on the same portions of the upper as said first-named wipers at the sides only of the toe to press the upper inwardly against the last and wipe it heightwise of the last, said ad-

ditional wipers being adjustable in directions lengthwise of the last relatively to said first-named wipers.

6. In a lasting machine, wipers for pressing an upper inwardly against a last and wiping it heightwise of the last around the end and along the sides of the toe, additional wipers arranged to act on the same portions of the upper as said first-named wipers at the sides only of the toe to press the upper inwardly against the last and wipe it heightwise of the last, and bars connected to said additional wipers and movable lengthwise in directions widthwise of the last to carry the additional wipers into positions to operate on the upper, said bars being mounted for swinging movements in directions lengthwise of the last to adjust the additional wipers relatively to said first-named wipers.

7. In a power-operated lasting machine, wipers for pressing an upper inwardly against a last and wiping it heightwise of the last around the end and along the sides of the toe, additional wipers arranged to act on the same portions of the upper as said first-named wipers at the sides of the toe to press the upper inwardly against the last and wipe it heightwise of the last, and power-operated means for controlling said additional wipers comprising parts relatively movable at the will of the operator to prevent the additional wipers from operating on an upper during the operation of the machine.

8. In a power-operated lasting machine, wipers for pressing an upper inwardly against a last and wiping it heightwise of the last around the end and along the sides of the toe, additional wipers arranged to act on the same portions of the upper as said first-named wipers at the sides of the toe to press the upper inwardly against the last and wipe it heightwise of the last, power-operated means connected to said additional wipers for controlling them, and means for disconnecting the additional wipers from said power-operated means and for retaining them in positions such as to prevent them from operating on an upper during the operation of the machine.

9. In a power-operated lasting machine, wipers for pressing an upper inwardly against a last and wiping it heightwise of the last around the end and along the sides of the toe, additional wipers arranged to act on the same portions of the upper as said first-named wipers at the sides of the toe to press the upper inwardly against the last and wipe it heightwise of the last, a power-operated member for controlling said additional wipers, mechanism for normally connecting said member to the additional wipers, and means for disconnecting said mechanism from the power-operated member and for locking the mechanism in position to hold the additional wipers retracted and thus prevent them from operating on an upper during the operation of the machine.

10. In a lasting machine, wipers for pressing an upper inwardly against a last and wiping it heightwise of the last around the end and along the sides of the toe, additional wipers arranged to act on the same portions of the upper as said first-named wipers at the sides only of the toe to press the upper inwardly against the last and wipe it heightwise of the last at the time when said first-named wipers are thus acting on the upper, and means for clamping the marginal portion of the upper on said additional wipers for

applying a pull to the upper as it is wiped heightwise of the last.

11. In a lasting machine, wipers for wiping an upper heightwise of a last around the end and along the sides of the toe and for thereafter wiping the marginal portion of the upper inwardly over an insole on the last, additional wipers arranged to act on the same portions of the upper as said first-named wipers at the sides only of the toe to wipe the upper heightwise of the last at the time when said first-named wipers are thus acting on the upper, and means for operating said additional wipers to begin the wiping of the marginal portion of the upper inwardly over the insole before said first-named wipers wipe it inwardly.

12. In a lasting machine, wipers for wiping an upper heightwise of a last around the end and along the sides of the toe and for thereafter wiping the marginal portion of the upper inwardly over an insole on the last, additional wipers arranged to act on the same portions of the upper as said first-named wipers at the sides only of the toe to wipe the upper heightwise of the last at the time when said first-named wipers are thus acting on the upper, and spring means arranged to hold said additional wipers pressed inwardly against the upper in the wiping of the upper heightwise of the last and thereafter to force them inwardly over the edge of the insole in wiping engagement with the upper before said first-named wipers wipe it inwardly.

13. In a lasting machine, wipers for wiping an upper heightwise of a last around the end and along the sides of the toe, said wipers being mounted for bodily movements lengthwise of the last and for swinging movement widthwise of the last to wipe the marginal portion of the upper thereafter inwardly over an insole on the last, additional wipers arranged to act on the same portions of the upper as said first-named wipers at the sides only of the toe to wipe the upper heightwise of the last, and means for imparting to said additional wipers rectilinear movements inwardly over the insole in directions substantially perpendicular to the edge of the insole to begin the wiping of the marginal portion of the upper over the insole before said first-named wipers wipe it inwardly.

14. In a lasting machine, wipers for wiping an upper heightwise of a last around the end and along the sides of the toe, said wipers being mounted for bodily movements lengthwise of the last and for swinging movements widthwise of the last to wipe the marginal portion of the upper thereafter inwardly over an insole on the last, additional wipers arranged to act on the same portions of the upper as said first-named wipers at the sides only of the toe to wipe the upper heightwise of the last, and spring means arranged to hold said additional wipers pressed inwardly against the upper in the wiping of the upper heightwise of the last and thereafter to force them inwardly over the insole in directions substantially perpendicular to the edge of the insole to begin the wiping of the marginal portion of the upper over the insole before said first-named wipers wipe it inwardly.

15. In a lasting machine, wipers for wiping an upper heightwise of a last around the end and along the sides of the toe, said wipers being mounted for bodily movements lengthwise of the last and for swinging movements widthwise of the last to wipe the marginal portion of the upper thereafter inwardly over an insole on the last,

- additional wipers arranged to act on the same portions of the upper as said first-named wipers at the sides only of the toe to wipe the upper heightwise of the last, means for clamping the 5 marginal portion of the upper on said additional wipers for applying a pull to the upper as it is wiped heightwise of the last, and means for imparting to said additional wipers movements inwardly over the insole in directions substantially 10 perpendicular to the edge of the insole in wiping engagement with the upper and for thereafter holding them stationary with the upper clamped thereon by said clamping means as said first-named wipers move inwardly over the insole.
- 15 16. In a lasting machine, wipers for pressing an upper inwardly against a last and wiping it heightwise of the last around the end and along the sides of the toe, said wipers being movable lengthwise and widthwise of the last to wipe the 20 marginal portion of the upper thereafter inwardly over an insole on the last, and additional wipers arranged to act on the same portions of the upper as said first-named wipers at the sides only of the toe to press the upper inwardly 25 against the last and wipe it heightwise of the last, said additional wipers being constructed and arranged to present wiping edges inclined heightwise of the last toward the end of the toe in a direction away from the edge of the insole to 30 give them a tendency to deflect the upper toward the end of the toe in wiping it heightwise of the last and thus to compensate for the tendency of said first-named wipers to deflect it in a heelward direction in wiping its marginal portion inwardly over the insole.
- 35 17. In a lasting machine, the combination with means for positioning a last bottom upward, of wipers for pressing an upper inwardly against the last and wiping it heightwise of the last 40 around the end and along the sides of the toe, and additional wipers positioned above said first-named wipers and arranged to press the upper inwardly against the last and to wipe it heightwise of the last at the sides only of the toe to 45 supplement the wiping action of said first-named wipers in those locations.

18. In a lasting machine, the combination with means for positioning a last bottom upward, of wipers movable upwardly to wipe an upper heightwise of the last around the end and along the side of the toe, and additional wipers arranged in substantially contiguous relation to the top faces of said first-named wipers and movable upwardly with them to wipe the upper heightwise of the last at the sides only of the toe. 5

19. In a lasting machine, the combination with 10 means for positioning a last bottom upward, of wipers movable upwardly to wipe an upper heightwise of the last around the end and along the sides of the toe, additional wipers arranged to rest on the top faces of said first-named wipers 15 and movable upwardly with them to wipe the upper heightwise of the last at the sides only of the toe, and means for pressing said additional wipers inwardly against the upper independently of the first-named wipers. 20

20. In a lasting machine, the combination with means for positioning a last bottom upward, of wipers movable upwardly to wipe an upper heightwise of the last around the end and along the sides of the toe, additional wipers arranged 25 to rest on the top faces of said first-named wipers and movable upwardly with them to wipe the upper heightwise of the last at the sides only of the toe, and means for imparting to said additional wipers inward and outward movements 30 relatively to the first-named wipers.

21. In a lasting machine, the combination with means for positioning a last bottom upward, of wipers movable upwardly to wipe an upper heightwise of the last around the end and along 35 the sides of the toe, additional wipers arranged to rest on the top faces of said first-named wipers and movable upwardly with them to wipe the upper heightwise of the last at the sides only of the toe, and members connected to said additional wipers for controlling them, said members 40 being mounted for upward and downward swinging movements as said first-named wipers are raised and lowered. 45
